UNITED STATES PATENT OFFICE.

JOHN M. RILEY, OF NEWARK, NEW JERSEY.

PUNCHING-MACHINE.

SPECIFICATION forming part of Letters Patent No. 428,414, dated May 20, 1890.

Application filed April 5, 1889. Serial No. 306,105. (No model.)

To all whom it may concern:

Be it known that I, JOHN M. RILEY, a citizen of the United States, residing at Newark, in the county of Essex and State of New Jersey, have invented certain new and useful Improvements in Punching-Machines; and I do hereby declare the following to be a full, clear, and exact description of the invention, such as will enable others skilled in the art to 5 which it appertains to make and use the same, reference being had to the accompanying drawings, and to letters of reference marked thereon, which form a part of this specification.

The object of this invention is to obtain a 15 direct reliable central vertical motion to the punch or tool shaft in a vertical punching-machine in a simple manner.

The invention consists in the improved 20 punching-machine, and the combination and arrangement of parts thereof, as will be hereinafter more fully set forth, and finally embodied in the claim.

Referring to the accompanying drawings, in which like letters of reference indicate corresponding parts in each of the several figures, Figure 1 is a front elevation of a vertical punching-machine embodying my improvement, with part of the bed-plate in section. Fig. 2 is a vertical section through line 30 x . Fig. 3 is a cross-section through line y . Fig. 4 is a section on line z , showing the arrangement of a loose cylindrical sleeve on the driving-shaft; and Fig. 5 is a section through line x' , Fig. 1, showing a cam-wheel 35 with cam projection secured to the main shaft.

In said drawings, A represents the frame of a punching-machine, in which revolves in suitable bearings $v v$, Fig. 4, a driving-shaft a , provided with loose driving-pulley b , which 40 also serves as a balance-wheel. On this shaft is secured an eccentric c (shown in Fig. 2) for operating a tool-shaft d by means of sliding bearings $e e$ on top of a flat projection d' on the upper end of the tool-shaft d .

On the upper side of the bearings e is a 45 plate f , secured to the projection d' by bolts $g g$, of sufficient length to allow the bearings $e e$ to slide between them on slides or ways 6, Fig. 2.

From the upper surface of the plate f extends a rod or shaft h , which moves in bearings in the upper part of frame A and serves

as a steadyng-guide for the tool-shaft d . To the bottom of the shaft d is secured an adjustable guide-block and tool-holder i , with 55 openings $k k$, to allow free access to nuts $m m$, for securing and adjusting the guide-block to the tool-shaft d . This guide-block and tool-holder i is provided on one side with angular projections $n n$, to slide in corresponding recesses in the frame A, as shown in Fig. 3. Opposite these recesses are secured to the frame metallic bars or rods $o o$, provided with 60 slots on their inner sides adapted to receive steel bars $p p$, which serve as slides for the 65 other side of the guide-block i . These slide-bars $p p$ are adjustable laterally by means of bolts $r r$, as shown clearly in Fig. 3.

Upon the bottom of the guide-block and tool-holder i is formed an annular shoulder s , 70 to receive a punch or tool t , which is held in position by a set-screw s' . To the bottom of the frame and directly under the punch or tool is secured by any desired means a bed or block u of ordinary construction. Upon 75 the driving-shaft a , and near its ends, are firmly secured collars $w w$, Fig. 1, to prevent lateral motion or play to the shaft when in operation. Within the bearings on which the driving-shaft revolves are fitted and adjusted loose perforated cylindrical collars l , 80 extending the whole length of the bearing, and surrounding the main shaft and held in position by the bearings by the rigid collars $w w$, as shown in Fig. 4, where one of the 85 bearings is shown in section. These collars $l l$ are loosely arranged on the shaft and can turn in any direction or be at rest while the press is in operation. The perforations in the collar l allow the lubricating material to 90 come directly in contact with the shaft when a lubricating material is employed; but such lubricating material is not necessary, as the collars being loose on the shaft and free to move in either direction, there could be no 95 perceptible friction, as will be manifest.

In Fig. 5 of the drawings is shown in section an ordinary cam-wheel 3 , with cam projections 4 rigidly secured to the shaft a for engaging a rod or bar connected with a pivoted lever connected with the engaging and disengaging clutch mechanism on the end of the shaft for stopping and starting the press, as shown in Fig. 1. The loose driving-pulley

is also connected with the clutching mechanism.

I have not described in detail the clutching mechanism, as I make no claim to it specifically, as any ordinary clutching mechanism can be used.

By providing the punch or tool shaft with the upward extension *h* and the guide-block *i* all lateral movement in any direction is entirely prevented and a positive and direct central vertical movement is imparted to the punch or tool shaft.

By the use of the eccentric on the main shaft working in the sliding bearings great power and steadiness and uniformity of motion are imparted to the tool-shaft, as by the revolution of the eccentric the bearings *e e* will move slightly forward and back between the parts *f* and *a'*, on which they are adapted to slide.

By means of the screws *m m* on the guide-block and tool-holder the punch or tool can be adjusted to any thickness of metal to be punched.

Having thus described my invention, what I claim as new, and desire to secure by Letters Patent, is—

In a punching-machine, the combination of the frame having the notches and bars formed with grooves, the tool-holder having lugs or ribs engaging said notches, and bars fitting in said grooves, the tool-shaft having the clamping-nuts thereon and formed with the flat projection, the plate having the extension or guiding-stem, the bearings between the plate and projection, the driving-shaft having the eccentric for engaging said bearings, the perforated sleeve on the driving-shaft, and the collars on said shaft, all arranged for operation as described.

In testimony that I claim the foregoing I have hereunto set my hand this 2d day of April, 1889.

JOHN M. RILEY.
